UNITED STATES PATENT OFFICE.

JOHN WALTER FRYER, OF ST. LOUIS, MISSOURI.

COMBINATION FURNITURE.

Application filed April 15, 1926. Serial No. 102,221.

My invention has relation to improvements in convertible furniture, one piece of furniture being adapted for purposes of a bed, table or settee; it consists in the novel features of construction more fully set forth in the specification and pointed out in the claims.

Briefly, the invention consists in a pair of juxtaposed supporting members suspended by hangers from spaced supporting frames, said supporting members when suspended in their lowermost position, serving the purpose of a bed. These supporting members are capable of rotation to an inverted position in a plane in line with the upper surface of the supporting frames for the purpose of conversion into a table, and either section may be adjusted to a position adjacent and perpendicular to the other section when the invention is adapted for the purpose of a settee or divan. Obviously resilient springs are provided on the supporting members over which is placed a mattress when the furniture is in the condition of a bed, said springs and mattress, however, coming on the inner side of the supporting members when they have been moved to the table position.

The advantages of the invention are obvious in that one piece of furniture may be made to serve the purposes of three by a simple adjustment of the parts. In addition to providing a piece of furniture with this three-fold function, it is the object to constitute the invention with as few parts as possible and at the same time provide rigidity and cheapness of manufacture. Further objects of the invention are better apparent from a detailed description in connection with the accompanying drawings, in which—

Fig. 1 is a top plan of the furniture when the supporting members are in a position to form a bed; Fig. 2 is a combined side elevation and vertical longitudinal section taken on the line 2—2 of Fig. 1; Fig. 3 is a sectional enlargement of the left hand end of the supporting member of the bed shown in Fig. 2; Fig. 4 is an enlarged cross sectional detail taken on the line 4—4 of Fig. 6; Fig. 5 is an end elevation of the invention with part broken away when the supporting members are in suspended position to constitute a bed; Fig. 6 is an end elevation of the invention with parts broken away when the supporting members are elevated and inverted for the purpose of constituting a

table; Fig. 7 is an end elevation of the invention with the supporting members positioned so as to constitute a settee; Fig. 8 is a perspective view of one of the brackets 60 from which the supporting members are suspended; Fig. 9 is a perspective view of one of the hangers by which the supporting members are suspended from the brackets; Fig. 10 is a cross sectional detail taken on the line 10—10 of Fig. 2; and Fig. 11 is a perspective view of a fragment of a supporting member looking toward one end 65 showing the locking key whereby said member is held in fixed relation to the hanger. 70

Referring to the drawings, 1, 1 represent supporting frames and constitute end frames when the invention is in the position of a bed. From the under side of the cross rails 2 of each supporting frame, two brackets 3, 3, are 75 suspended, said brackets being spaced one-fourth the length of the rail 2 from each end thereof. The brackets 3 have sockets 4 formed on their lower extremities and a recess 5 is formed in the inner bounding wall 80 6 of the socket 4. It will be observed that the recess 5 does not extend to the same depth as the socket 4 for a purpose that will presently appear. The aligning brackets 3, 3 depending from opposite top rails 2, 2 are 85 in opposed relation and constitute a pair, from which pair of brackets a supporting member A is suspended by means of hangers 7, 7 in the following manner: Each hanger 7 has a spindle 8 projecting from its upper end, said spindle terminating in an enlarged disc 9, said spindle and disc being adapted to rest and rotate in the recess 5 and socket 4 of hanger 3.

Each supporting member A consists of a 95 box-like frame 10 in which are distributed a plurality of springs 11, said springs projecting slightly above the sides 12 of the box frame 10, and a mattress 13 rests on the springs 11, said mattress being held in place 100 by a number of marginal mattress holders 14. The holders 14 each consist of a rod 15 which passes through an opening 16 in the mattress and through an opening 17 in the side rails 12 and end rails 18 of the frame 105 10. These rails 12 and 18 are provided with marginal sockets 19 each of which receives the inner end of rod 15, said end being threaded and having secured thereon a disc 20 between which and the top of the socket 110 19 a coiled spring 21 is secured. The upper end of the rod 15 has a disc 22 fixed on it

and as the rod 15 is drawn inwardly by the tension of the spring 21, the disc 22 on the outer end of the rod bears down on the margin of the mattress 13 to hold the same in place. Fixed to the upper surface of each end rail 18 of the box frame 10 is a bearing 23 and bearing cap 24, each of which is provided with a shouldered semi-circular recess 25 in which is received a trunnion 26 formed on the extension of a spindle 27 projecting from the lower part of the hanger 7. The bearing 23 is provided with the movable cap 24 to permit the trunnion 26 to be received within the bearing, said bearing and trunnion being rotatable relative one to the other. Each section A is thus suspended from a pair of hangers 7, the sections being rotatable relative to the hangers and the hangers themselves being rotatable within the socket 4 of the bracket 3.

Obviously, the section must be held in fixed relation to the hanger 7 for any given position as must also the hanger with relation to the bracket 3. The hanger 7 is held against movement in the bracket by means of a pin 28 which is insertible through an opening 29 in the rear wall of the socket 4 and adapted to engage in one of three notches, 30, 30' and 30'' ninety degrees apart on the periphery of the disc 9. When the sections A are in the position to form a bed, each pin 28 is disposed in notch 30'' of each hanger 7, and when the sections are inverted and elevated to form a table as shown in Fig. 6, the pin 28 is in the notch 30; when either section is in a vertical position as shown in Fig. 7, the pin is in the notch 30'.

The bracket 7 is provided with lateral extensions 7', 7'' to which are secured wear plates 31, 31, said plates being in contacting relation with wear plates 32, 32 secured to each end rail 18. An elongated opening 33 is provided in the plates 31 and 32 near their inner ends, the opening 33 being elongated laterally so as to prevent a lock key 34 from slipping out of the openings, the lock key having a downwardly turned inner extension 35 which makes it impossible to remove the key 34 from the openings except when it is turned in the direction so that the extremity 35 is co-extensive with the opening 33. It will be observed by referring to Figs. 5, 6 and 7 that the outer extremity 36 of the lock key will hold this key by gravity in the same position irrespective of the positions of the sections A, that is, with the extremity 36 pointing downwardly. As the elongated opening 33 does not point downwardly for any operative position of the section A, the key cannot become displaced from its locking position.

Obviously, clearance must be provided between the ends of the section A and the supporting frames 1, the result of which is that when the sections A are raised as shown in

Figs. 4 and 6 to form a table, there will be a crack between the ends of the sections and the cross bar 2 of each end frame. A crack would be detrimental to the use of the table, so I have provided a seal therefor which 70 consists in a bar 37 pivotally mounted in a recess 38 formed along the inner edge of each cross bar 2, the bar 37 having a rod 39 extending through it, which rod is supported in plates 40, 40 embedded in the cross bar 75 2 near the extremities thereof.

Normally, the sections A, A are suspended in their lowermost position as shown in Figs. 2 and 5 to form a bed. However, if desired, these sections may be inverted and swung upwardly as shown in Fig. 6 to form a table. In performing this operation, it is obvious that the pins 28 and keys 34 must first be removed so as to permit a relative movement of the parts after which the sealing bars 37 are swung outwardly as shown in Fig. 4 and the sections A, A elevated into place in contact with the inclined edge 41 of each bar 37. When the sections A, A are raised, a continuous table surface is formed 90 of the under side of the box frames 10, sealing bars 37 and top surface of end bars 2, 2. If it is desired to form a settee, only one of the sections A is released from the locking pins after which it is rotated to the position shown in Fig. 7 (that is perpendicular to the other section A), the lock pins being then restored to hold the section in such position.

The springs 11 are not herein described in detail as they form the subject of a co-pending application filed by me on the third day of April, 1926 under Serial No. 99,564. Obviously, other types of springs may be used and the specific features of construction 105 therein shown may be departed from any such particulars as come within the purview of a skilled mechanic.

Having described my invention, I claim:

1. A combination bed and table comprising supporting frames in spaced relation, a pair of brackets secured to the supporting frames, the lower end of each bracket terminating in a bearing, a pair of hangers pivotally mounted in the bearings of the brackets, said hangers each terminating at its outer end in a trunnion, a supporting member suspended from the hangers, said supporting member having bearings at each end, said bearings receiving the trunnions and being rotatable thereon, said supporting member being adapted to form a bed in its lowermost position, and being movable to a plane in line with the top of the supporting frames to form a table, and means for locking the supporting member in each of said positions.

2. A combination bed and table comprising supporting frames in spaced relation, a pair of brackets secured to the supporting 130

frames, the lower end of each bracket terminating in a bearing, a pair of hangers pivotally mounted in the bearings of the brackets, said hangers each terminating at 5 its outer end in a trunnion, a supporting member suspended from the hangers, said supporting member having bearings at each end, said bearings receiving the trunnions and being rotatable thereon, said supporting 10 member being adapted to form a bed in its lowermost position and being movable to a

plane in line with the top of the supporting frames to form a table, means for locking the supporting member in each of said positions, and means on the inside surface of said 15 supporting frames for closing the clearance space between said frames and supporting member when the latter is raised to form a table.

In testimony whereof I hereunto affix my 20 signature.

JOHN WALTER FRYER.
